UNITED STATES PATENT OFFICE.

SAMUEL SADLER, OF SAN FRANCISCO, CALIFORNIA.

DESIGN FOR A COMBINED LAMP AND SOUND AMPLIFIER.

Application filed August 5, 1924. Serial No. 10,387. Term of patent 3½ years.

To all whom it may concern:

Be it known that I, SAMUEL SADLER, a citizen of the United States, residing at San Francisco, in the county of San Francisco and State of California, have invented a new, original, and ornamental Design for Combined Lamps and Sound Amplifiers, of which the following is a specification, refer-

ence being had to the accompanying drawing, forming part thereof.

The figure is a perspective view of a lamp and sound amplifier showing my new design.

I claim:

The ornamental design for a combined lamp and sound amplifier, as shown.

SAMUEL SADLER.
